UNITED STATES PATENT OFFICE.

MICHAEL PARIDON, OF BARBERTON, OHIO, ASSIGNOR TO THE DIAMOND MATCH COMPANY, OF CHICAGO, ILLINOIS, A CORPORATION OF ILLINOIS.

PROCESS OF MAKING REINFORCED BOXES.

1,206,898.

Specification of Letters Patent.

Patented Dec. 5, 1916.

Application filed June 15, 1915, Serial No. 34,141. Renewed August 5, 1916. Serial No. 113,383.

To all whom it may concern:

Be it known that I, MICHAEL PARIDON, a citizen of the United States, and resident of Barberton, in the county of Summit and State of Ohio, have invented certain new and useful Improvements in Processes of Making Reinforced Boxes, of which the following is a specification.

The object of this invention is to provide a simple, efficient and economical process of making rectangular paper or paste-board boxes having reinforced end walls.

In carrying out my invention in the preferred way, I glue or otherwise secure at regular intervals apart to a strip of paper, paste-board or other suitable box material, transversely of the strip, sections of reinforcing material which are each in length substantially equal to the width of a box, and in width substantially twice the height of an end wall of a box. I then preferably slit the strip longitudinally thereof at or adjacent the ends of the sections, and score the strip longitudinally and transversely thereof, the longitudinal scoring being on lines interrupted by the longitudinal slits, and the transverse scoring being on lines adjacent the longitudinal edges of the sections. I then cut the strip on transverse lines medially of the respective sections to form box blanks. I then bend the margins of each of the blanks along its longitudinal score lines to form side walls. I then bend inward the slitted ends of the sides to produce corner folds, and finally I bend the reinforced portions of the blank on its transverse score lines and secure such portions to the opposing corner folds to form end walls. The resulting product is a rectangular box comprising a bottom, side walls and effectively reinforced end walls.

In the drawings which illustrate the preferred mode of procedure—Figure 1 represents a fragment of a strip of paper or paste-board following the step of applying the spaced reinforcing sections thereto. Fig. 2 represents the reinforced strip after it has undergone the slitting and scoring steps. Fig. 3 is a plan of a box-blank as severed from the strip shown in Fig. 2. Fig. 4 is a perspective view of the completed box.

Referring to the drawings, 5 designates the strip of paper, paste-board or other suit-

able box material; 6 the reinforcing sections thereon of similar material; 7 the longitudinal slits in the strip at the ends of the sections, and 8 and 9 the longitudinal and transverse score or fold lines respectively in the strip. The strip structure is cut transversely thereof, on lines medially of the reinforcing sections, as indicated in Fig. 2, thus producing box blanks of the character illustrated in Fig. 3, that is to say, each successive blank comprises a rectangular bottom portion *a*, reinforced end portions *b* and side portions *c* having end tongues *d*. Each of the blanks is folded as above described, the reinforced end walls being glued or otherwise secured to the corner folds constituted by the end tongues, to produce the box shown in Fig. 4; which box comprises a bottom *a*, side walls *c* having end corner folds *d*, and reinforced end walls *b*.

In practising the process above described there is no waste material in the formation, application or division of the reinforcing sections. These sections can be readily cut in continuous succession from a strip of material of proper width, and as rapidly as they are cut they can be applied to the body strip in spaced relation to each other. In the severance of the strip into box blanks each of the sections is medially divided to provide reinforcing elements for the adjacent end portions of two blanks.

I claim:

1. A process of making reinforced boxes, which consists in securing at regular intervals apart to a strip of box material transverse reinforcing sections of material of less length than the width of the strip, cutting the strip on transverse lines medially of the sections to form successive box blanks having reinforced end portions; bending the longitudinal margins of each of the blanks beyond its reinforced portions to form the side walls of a box, and bending up the reinforced end portions of the blank to form the end walls of the box.

2. A process of making reinforced boxes, which consists in securing at regular intervals apart to a strip of box material transverse reinforcing sections of material of less length than the width of the strip; slitting the strip longitudinally thereof adjacent the ends of the sections; cutting the strip on

2
transverse lines medially of the sections to form box blanks; bending the longitudinal margins of each of the blanks beyond its reinforced portions to form the side walls of a box; bending inward the slitted portions at the ends of said margins, and bending and securing to said slitted portions the re-

inforced portions of the blank to form the end walls of the box.

Signed at Barberton in the county of ¹⁰ Summit and State of Ohio this 12th day of June A. D. 1915.

MICHAEL PARIDON.
